United States Patent Office.

WILLIAM H. McHENCH, OF COBLESKILL, NEW YORK.

Letters Patent No. 102,845, dated May 10, 1870.

IMPROVED LADDER.

The Schedule referred to in these Letters Patent and making part of the same.

To all whom it may concern:

Be it known that I, WILLIAM H. McHENCH, of Cobleskill, in the county of Schoharie and State of New York, have invented a new and useful Improvement in Ladders; and I do hereby declare that the following is a full, clear, and exact description thereof, which will enable others skilled in the art to make and use the same, reference being had to the accompanying drawings forming part of this specification.

This invention relates to a new and useful improvement in ladders, and consists in making the ladder self-supporting by connecting two ladders together forming a double ladder, as hereinafter described.

In the accompanying drawing—

Figure 1 is a sectional elevation of a double self-supporting ladder constructed according to my invention, the section being through the line $x x$ of fig. 2.

Figure 2 is a front elevation.

Similar letters of reference indicate corresponding parts.

A A represent two ladders or sets of rails and rounds, which may be identical in form and size, or nearly so.

They are connected at their top ends by a round, B, (loosely,) so that the two ladders may be folded up or spread apart at the bottom. By spreading the bottoms the double ladder is made self-supporting, as seen in fig. 1.

C is a platform directly above the double ladder, attached to two brackets D D.

The round B passes through these brackets, and the platform is supported thereby.

These brackets extend down with a slot, E, in each.

F F F F are arms, which are attached at one end to a round in each ladder, as seen at G G.

H is a rod, which passes through their other ends, as seen at I I; there are two pairs of arms arranged in this manner.

The connections G and I form joints, so that when the two parts of the ladder A A are folded or brought together, the rod H will slip up the slot E.

When the parts A A are extended, as seen in fig. 1, the platform C is maintained in a horizontal position by the arms F, while the parts of the ladder A A are prevented from spreading by the same means, thus forming a self-supporting ladder with a firm platform at its top.

These ladders may be made of any desired length, so as to adapt them to all the various purposes, for which step-ladders and other self-supporting ladders are used. For picking fruit or pruning trees, or for use in stores and dwellings, and in various other situations, this ladder will be found very valuable.

Having thus described my invention, I claim as new and desire to secure by Letters Patent—

In duplicate ladders, the brackets D D, attached at the vertex of the angle formed by the ladder to the rod B, and provided with slots, closed at their lower ends, to prevent the lateral spread of the two parts beyond a certain limit.

The above specification of my invention signed by me this 10th day of September, 1869.
